UNITED STATES PATENT OFFICE

CHARLES E. FOOTE, OF NUNDA, NEW YORK, ASSIGNOR TO THE FOOTE COMPANY, INC.,
OF NUNDA, NEW YORK, A CORPORATION OF DELAWARE

BOOM DRIVE

Application filed August 20, 1928. Serial No. 300,832.

My invention relates to new and useful improvements in concrete pavers and more especially to the boom drive.

As is well known to those skilled in the art, concrete pavers are generally provided with a boom at their one end, on which travels back and forth a bucket and which bucket receives the aggregates after they are thoroughly mixed in the drum of the paver, after which the bucket is pulled by a cable out along the boom, the bucket automatically opened and then returned to its starting place.

The drive cable and the mechanism for operating this cable and its connection with the bucket is known as the "boom drive."

The present invention contemplates new and novel arrangements for the manner of driving the cable and thus the bucket, and especially as used in conjunction with the well known Foote paver.

Still another object of the invention is to provide a boom drive of the planetary type to thereby provide a smoother action in the driving of the bucket and to overcome the sudden impulses or jerking of the bucket which is inherent with the other forms of boom drives.

Still another object of the invention is to provide a boom drive of the planetary type and to also mount on one of the driving shafts the planetary arrangement for operating the discharge chute of the mixer.

In two of my former patents, to wit:—No. 1,356,615 and No. 1,394,160 planetary mechanism for the discharge chute is shown and in those instances the planetary mechanism is mounted on the front end of the paver and at one side thereof. Now one of the objects of the present invention is to place this planetary arrangement up over the chute where it is more conveniently arranged and to mount it on the same shaft that operates the planetary boom drive.

Still another object of the invention is to provide a boom drive consisting of two planetary gear cable drums mounted directly above the inner pivotal end of the boom whereby the cable will run directly from the planetary systems downwardly beneath the

sheaves mounted on the inner end of the pivotal boom, and thereby make it unnecessary to use the ordinary intermediate guide sheaves.

Still another object of the invention is to provide a very compact and simple construction that does away with the usual set of bevel gears as the winding drums revolve at right angles from the winding drums used in the previous constructions, the axis of these winding drums being parallel to the axis of the mixing drum of the paver.

Still another object of the invention is to provide two like planetary cable drums for driving the cable that moves the bucket out along the boom, these planetary cable drums being so arranged that when running, they always run in the same direction with relation to each other and the cable is so arranged so that as one drum takes up, the other pays off, and either drum may be quickly thrown into operation to thus cause the other drum to follow and drive the bucket outwardly along the boom or inwardly as desired.

Still another object of the invention is to provide these two planetary cable drums which are normally both idle, with a sprocket chain, so that when one is driving and the other idle they will both be travelling at the same rate of speed.

Still another object of the invention is to provide these two planetary cable drums, both operated from one lever and so arranged that either one may be quickly thrown into active operation, and the idle drum in either instance being idle in the sense that it is simply being rotated by the active drum, and of course, in the same direction.

With these and other objects in view, the invention consists of certain new and novel arrangements and combination of parts as will be hereinafter more fully pointed out and described in the claims.

Referring now to the drawings showing a preferred embodiment of the boom drive:—

Fig. 1 is a sectional view taken on line 2—2 of Fig. 2, and showing the two planetary cable drums and their operative connections,

Fig. 2 is a fragmentary front elevation of the boom drive and a fragmentary portion

of the boom and bucket, the boom being turned sharply to one side for the sake of clearness of illustration,

Fig. 3 is a fragmentary view of the two planetary cable drums, parts being omitted for the sake of clearness of illustration, and showing the manner in which the desired brake drum is applied to actuate either of the drums,

Fig. 4 is a side elevation, partly in section, showing the arrangement of the boom drive and also of the planetary discharge chute mechanism,

Fig. 5 is a sectional view on line 5—5 of Fig. 4 and showing the manner of operating the planetary discharge chute mechanism,

Fig. 6 is a side elevation of the boom, parts being in section and parts being removed for the sake of clearness, and showing the threaded cable, and

Fig. 7 is a top plan view of the same.

At the outset it might be mentioned that in Patents No. 1,356,615 and No. 1,394,160, there is shown two arrangements for a planetary discharge chute mechanism and the present invention contemplates not only a new and novel arrangement for the boom drive but also contemplates providing and mounting a planetary discharge chute mechanism up on the driving shaft of the planetary boom drive.

Referring now more particularly to the several views and to Fig. 2 for the moment, there is shown the two front uprights 1 that are supported on the paver frame (not shown), and it will be understood that the type of paver is of the well known Foote type, as shown in various patents such as No. 1,443,354, No. 1,562,751, etc., there being a support on which is mounted a caterpillar form of tractor, upon which support is a frame, while on this frame there is mounted the mixing drum and power plant. There is also a skip, the boom and bucket, and means for operating the various parts.

Extending across the top to the two uprights is the top frame 2, while also extending from the two frames 1, is the large casting 3 which is provided with the central hollow cylinder 4, which cylinder is positioned directly over the discharge 5 of the mixing drum (not shown).

Also pivotally mounted to the front of the paver is the boom 6 which is provided with a segmental gear 7 that is in turn operated by the small worm shaft 8 on which there is a sprocket 9 operated by the chain 10, which in turn passes over the sprocket 11 and turned by the shaft 12, which latter will be provided with a wheel (not shown) for its operation.

On the inner end of the boom 6 are mounted two sheaves 13, which it will be seen are directly beneath the hollow chamber 4, which chamber it will be remembered is part of the casting 3, so that the one bight of the cable

14 may pass directly downwardly from one drum (about to be described), through the chamber 4 and directly beneath the sheaves 13, where it is connected to a shaft 15 of the bucket door opening and closing mechanism and then extend outwardly over a sheave 13a at the outer end of the boom and back to the bucket or trolley and then up to the other drum.

The bucket door opening and closing mechanism is well illustrated in the application filed by me on June 15, 1926, and bearing Serial No. 116,126 and also the patent to Devinney, No. 1,640,980 shows the form of bucket that is used with the Foote paver, and it is simply thought necessary to mention here briefly that there is a toggle or throwover connected with the doors of the bucket whereby when the cable is pulled in one direction, the bucket will travel outwardly and the doors will remain in a closed position until the cable is reversed, when the doors of the bucket will then be opened, and means may be provided whereby the bucket doors are closed when the bucket again reaches its inner end of travel.

In Fig. 2 there is shown the connecting arm C that extends down to the links which are fastened to the door of the bucket (not shown), and the bucket illustrated may be that of the said "Devinney" type above mentioned, although any of the Foote paver type of buckets may be used.

It will be understood that the present application relates to the arrangement and position of the drive cable and the manner in which it is driven, together with the means employed; the cable, it will be remembered, functioning to advance and retract the bucket along the boom, and also being connected to the "door operating means" of the bucket.

Still referring to Fig. 2 there is shown mounted on the boom, the trolley 16 having the arms 17 that support the Devinney bucket 18, one bight of the cable being shown in dotted lines as passing over the sector in one direction and being connected to the rock shaft 15, and the other bight of the cable passing over the sector in the other direction and connected thereto. This shaft 15 is the one to which the links are connected that extend down to the doors of the bucket and the sector and its manner of arrangement is the one shown in the application above mentioned, to wit, bearing Serial No. 116,126, filed June 15, 1926.

It is desired that as one bight of the cable travels in one direction and pays off a drum that the other bight of the cable be taken up. The present invention contemplates accomplishing this by providing two cable drums A and B, one portion or bight of the cable being wrapped around the drum A and the other being wrapped around the drum B. These two drums are centrally positioned at the end of the paver and directly above the

inner pivotal end of the boom and are so arranged that as the cable winds up on the drum A it will pay off the drum B and vice versa.

These two drums are parts of two planetary systems which will shortly be described more in detail.

Referring now to Fig. 1 there is shown in dotted lines a ring gear 19 which is mounted on the mixing drum (not shown), and in turn 10 meshes with the driven gear 20 shown in dotted lines, to the far right of the drawing.

This driven gear 20 is rigidly mounted on the main drive shaft 21, which shaft is securely mounted in the upper framework 22 15 of the paver.

There is a planetary gearing system 23 mounted on the shaft 21 for operating or partly revolving the discharge chute 5 of the paver, this planetary discharge arrangement 20 being very similar to the construction shown in the previous mentioned Patents No. 1,356,615 and No. 1,394,160. In those patents, however, the planetary mechanism was mounted on a shaft directly to one side of the chute 25 discharge, whereas in the present instance it is mounted above the chute discharge and on the driving shaft 21 as heretofore mentioned.

As may be seen there is a sun gear 24 rigidly mounted on the shaft which engages the 30 usual planets 25, which meshes with the ring 26, there being the holding brake band 27 and the eccentrically mounted pitman 28, which extends down to the spout or chute of the mixer.

As is well known to those familiar with 35 pavers and discharge chute mechanisms, there is generally provided a chute which extends up into the drum of the mixer and this is rocked from one position to another so that 40 in one position, the aggregates in the drum will, as they approach the top of the drum, fall into the discharge chute and be discharged from the drum, whereas when the discharge chute is rocked within the drum to a 45 normal position, the aggregates will fall as before as they approach the top of the drum, but the chute being to one side, the aggregates will fall to the bottom of the drum and will continue to do so until the chute is rocked 50 back to a position to catch the aggregates and discharge them.

I have simply outlined the chute in the present drawings as it is thought that it is only necessary to show the chute in outline 55 and the pitman connected thereto, and it will be understood that when the pitman is in one position it will hold the discharge chute in its discharging position and may be quickly moved to its opposite position, where the discharge chute will be in an inoperative position.

In Fig. 5 there is shown the means for actuating or operating the brake on the planetary discharge for the chute comprising the connecting rod 29 which is connected to the lever

30 so that when the lever 30 is operated the brake will be applied and the discharge chute rocked from one position to the other.

In Fig. 4 there is shown the mounting of the lever 30, this being fixed at its lower end to the shaft 31 while the operating rod 29 is fastened to the arm 32 on the shaft 31. There is also shown a small spring 33 connected to the lever 30 so that the small roller 34 will normally be held in engagement with one of the notches 35 of the planetary gearing 23. 75

When the handle 30, therefore, is pulled toward the operator (Fig. 4) it will apply the brake and release the small roller 34 from its notch 35 and permit the discharge chute to be rocked through the eccentric movement of the pitman connected to the discharge chute, as will be clearly understood. 80

Referring now to a very important feature of the invention, and that is the boom drive mechanism, there will be seen fixedly mounted on the drive shaft 21, the gear 36, which in turn meshes with gear 37, which latter gear is mounted on a short shaft 38 which shaft is mounted in the bearing 39 and in the front top rail 2. Thus a turning movement of the shaft 21 in one direction will turn the shaft 38 in the opposite direction. It will also be seen in Fig. 1 that the cable drum A is mounted on the shaft 21 and that the cable drum B is mounted on the shaft 38, so that when the drum A is temporarily locked with relation to its shaft 21, it will turn in an anti-clockwise movement and when B is temporarily locked to its shaft 38, it will turn in a clockwise direction. 90

Explaining somewhat more specifically these two cable driving drums, it will be understood that they are alike and each a part of the planetary gearing system. Glancing at 105 drum A it will be seen that there is keyed to the drive shaft 21, the sun gear 40, which in turn meshes with the planets 41, that are respectively mounted on the short stub shafts 42, which stub shafts 42 are mounted in a part of the casing or brake drum 43 on the outer side of which is secured the brake band 44, while the planets also mesh with the internal ring gear 45 that is a part of the drum. 110

From this it will be understood that the drum A is normally idle on the shaft 21, but when the brake band 44 is applied, the drum A is revolved by the action of the sun gear and planets as the brake drum is held against movement. 115

On the outer surface of the hub 49 of the drum A is keyed the sprocket wheel 46 over which the sprocket chain 47 is secured, which also meshes with the sprocket wheel 48 that is mounted on the hub 49 of the planetary 120 cable drum B.

This drum B is identical with the drum A just mentioned, it having the sun gear 50, the planets 51, the brake drum 52 and the brake band 53 and the internal ring 54, but when 125

locked to its shaft by the brake band it will turn in the opposite driving direction to drum A.

Through the medium of the sprocket wheels 36 and 37 on the two shafts it will be understood that the rotation of the drums are always in the same direction to each other, and both travel at the same rate of speed.

It will be remembered that both drums A and B are normally idle on their respective shafts and if drum A is temporarily locked with relation to its shaft it will turn in one direction and cause the drum B which is normally idle on its shaft, to revolve with it in the same direction. However, should drum B be temporarily locked with relation to its shaft, it will revolve in the opposite direction and cause the drum A to follow in the same direction with it.

Now, I have shown a means for quickly applying either of the respective brake bands 44 and 53. Referring to Fig. 3 it will be seen the hand-lever 55 is loosely mounted at its bottom on the heretofore mentioned shaft 31 and has the connecting rod 56 secured thereto, which rod in turn is pivotally mounted to the small casting 57 which in turn is mounted on the small shaft 58 so that this casting may be rocked in either a right or left-hand direction. The brake band 44 that passes around the drum A is fastened at its upper end to the pin 59 and at its other end is buckled to the pin 60. In like manner the brake band 53 of the drum B is fastened at its one end to the pin 61 and at its lower end is buckled to the pin 62, these several pins being on the band brake head 63.

In like manner, by a rocking of the lever 55, we will say in a right-hand direction, in Fig. 3, the brake band about the drum A is tightened to thus cause the drum A to revolve, and the drum B being idle on its shaft will, due to the sprockets and chain 47, be revolved in the same direction to the drum A. Now the two bights of the cable 14 pass over the adjacent sides of drums A and B, as will be seen in Fig. 2, so that as the drum A is functioning and the bucket is moved outwardly, it will take up the cable on the drum A and the drum B being idled in the same direction, the other bight of the cable will be paying off of the drum B. Both drums are grooved for the reception of the turns of the cable.

In the opposite manner, if the lever 55 is forced inwardly, the drum B will be thrown into driving operation, which is in the opposite direction to wind its bight of the cable and the drum A being free to turn in the same direction as its brake band is loose, and will pay off the cable.

Thus it will be seen that a movement of the lever 55 in one direction will cause the cable to move the bucket out along the boom, the cable on one cable drum winding up as the bight on the other drum pays off, while a

reverse movement of the lever will cause the drums to function in the opposite direction and return the bucket inwardly along the boom.

The sector of course will be thrown when the cable is reversed to thus open the doors of the bucket, but this feature is not a part of the present invention and is shown in the pending application above mentioned.

It will be seen that the construction is relatively simple and does away with the usual set of bevel gears as these winding drums revolve at right angles from those used in any of the previous Foote constructions.

It also does away with the necessity of any intermediate guiding sheaves for the cable, as the cables extend directly from the drums down to and over the guiding sheaves on the inner pivotal end of the boom.

It will also be noticed that by using the chains and sprockets that the two drums travel at the same rate of speed and when one is driving and winding up the cable, the other is idling and paying off the cable and at the same rate of speed, which will be clearly understood.

Furthermore, it will be understood that there is no heavy impact or jar on the cable when starting or stopping the bucket. This is important as any continuous sudden impact or shock on the cable tends to stretch the same and makes it necessary to be continuously tightening the cable.

With this planetary cable driving arrangement the starting and stopping is controlled in a very smooth even manner and thus lengthens the life of all of the parts of planetary gearing.

Also, by locating the discharge chute mechanism up on the driving shaft of one of the planetary cable drums, it is out of the way and also simplifies the machine and lessens the number of parts.

It is only necessary to have two handles for this chute discharge mechanism and the boom drive mechanism, and of course, the less controls to operate, the less chance of confusion.

Lastly, it will be seen that the construction is a relatively simple one and does away with a great number of parts previously employed and at the same time functions in a simple and smooth manner as will be readily understood from the above description.

Many slight changes might be made without in any way departing from the spirit and scope of the invention.

Having thus described the same, what I claim as new and desire to hereby secure by Letters Patent, is:—

1. A boom drive for concrete pavers comprising a boom and bucket, a cable attached to the bucket for advancing and retracting the same along the boom, a planetary driving system including two drums, the inner ends of the cable attached respectively to the said

drums, said drums being normally idle, means for selectively driving either of said drums, and the drums interlocked with each other at all times.

5 2. A concrete paver having a boom and bucket and a cable extending along the boom for advancing and retracting the bucket along the boom, a planetary driving system including two driving cable drums horizontally mounted, both normally idle, means for selectively operating either of said drums, the rotary driving direction of the two drums being opposite to each other and the drums provided with sprockets and connected with a chain 10 so that the selected driving drum idles the other of the said drums in the same direction as the driving drum so that as part of the cable pays off one drum it takes up on the other.

20 3. A concrete paver having boom and bucket and cable attached to the bucket for advancing and retracting the same along the boom, a planetary driving system for the bucket comprising two drums for driving and retracting the cable, both of said drums being normally idle, the driving direction of the drums being opposite to each other and the drums permanently connected by a sprocket chain to each other so that as one drum drives 25 the other drum idles in the same direction so that as part of the cable pays off of one drum a part of the cable is taken up on the other drum.

4. A planetary boom drive for concrete 35 pavers, including drums planets and sun gears operably connected with said drums, and a cable, its inner ends wrapped respectively around the two said drums, the said drums being horizontally mounted, a boom 40 and bucket, said cable extending along the boom to the bucket for driving the bucket out and back along the boom, the driving direction of the drums being opposite to each other, means for selectively driving either of 45 the said drums and interconnecting means between the two drums for causing the driving drum to cause the idle drum to turn in the same direction and at the same rate of speed, whereby as one drum pays off the other 50 drum takes up the cable.

5. A boom drive for concrete pavers comprising a boom, a trolley on the boom and a bucket carried by the trolley, a cable passing out along the boom and connected to the said 55 trolley, means for driving the cable comprising a driving shaft and a planetary driving system including a drum idly mounted on said shaft, a stub shaft and means for driving the stub shaft in the opposite direction 60 from the driving shaft, a second cable drum on the said stub shaft, means for selectively causing either one of the drums to drive, and endless means connecting the two drums together so that as one drum drives the other 65 drum idles in the same direction and vice

versa, and as one drum pays off the cable the other drum takes up the cable.

6. A concrete paver comprising boom and bucket, planetary means for driving and retracting the bucket along the boom, comprising a cable, and two driving drums horizontally mounted above the boom, one for advancing the bucket and the other for retracting the bucket, means for selectively driving either of the said drums, and sprocket and chain 70 means for positively interconnecting the two drums to each other for causing the idle drum to idle in the same direction as the driven drum, whereby as the cable pays off one drum, it takes up on the other.

7. A boom drive for concrete pavers comprising a boom and a bucket and a cable, said cable connected to the said bucket, a planetary driving system including a cable drum having one end of the cable wound around the said drum and the said drum adapted to drive the cable and bucket in one direction, a second drum having the other end of the cable attached thereto and adapted to drive the cable and bucket in the other direction, means for selectively operating either of the said drums, and chain and sprocket means connecting the drums whereby when one drum drives the other drum idles in the same direction and as the cable takes up the one drum it pays 80 off the other drum.

8. A concrete paver having a boom pivotally mounted at its inner end on the paver, guide sheaves on the inner pivotal end, and a guide sheave at the outer end of the boom, a planetary driving system including two drums mounted on the paver directly over the pivotal end of the boom, a cable secured to said drums and extending directly from the surface of the drums to beneath the sheaves 100 on the inner pivotal end of the boom and extending out along the boom over the sheave at the outer end of the boom, a bucket mounted on the boom and connected with the cable, one of the said drums for driving the cable 105 and bucket outwardly and the other of said drums for moving the bucket inwardly, and means for selectively operating either of the said drums.

9. A concrete paver comprising a boom pivotally mounted at its inner end, a bucket mounted thereon, sheaves at the inner pivotal end of the boom, a planetary driving system including two drums mounted directly over the inner end of the boom, a cable connected 115 to said bucket and operated by either of the said two drums for alternately driving the bucket inwardly and outwardly, and the cable passing directly from the periphery of the drums down to and over the sheaves on the inner end of the said boom.

10. A concrete paver having a boom pivotally mounted at the forward end of the paver, a bucket mounted on said boom for inward and outward travel thereon, a cable 120

- for actuating said bucket, a planetary driving system including two drums for driving said cable and mounted on the said paver directly above said boom, and the axes of the said drums being parallel with the axis of the mixing drum of the paver, the cable having its inner ends secured to the said drums and passing over the adjacent faces of the said drums, sheaves on the inner pivotal end of the boom and a cable passing directly from said sheaves up to and over said drums, and means for selectively operating either of the said drums to move the bucket inwardly and outwardly on the said boom.
11. A concrete paver having a boom and bucket, a cable attached to said bucket, a planetary driving system including a drum for driving the bucket outwardly and a separate drum in said system for pulling the bucket inwardly and said drums being externally interconnected at all times, a driving and a driven shaft for operating both of said drums and said driving shaft adapted to be driven directly from the ring gear of the mixer.
12. A boom drive for concrete pavers comprising a planetary driving system including two cable driving drums, said drums mounted adjacent to each other and the axes of said drums extending longitudinally of the mixer and externally interconnected.
13. A concrete paver having a boom and bucket and a planetary gearing system, drums in the system for operating the bucket on the boom, a cable passing up and over the adjacent faces of the drums, chain and sprocket means extending across the outer faces of the drums for causing said drums to always rotate in the same direction with relation to each other so that as one drum pays off the other drum takes up the cable, said drums selectively operatively driven and means for selectively operating either of said drums.
14. A concrete paver having a boom pivotally mounted at the inner end of the said paver, sheaves at the inner end of the boom and a sheave at the outer end of the boom, a planetary driving system including two drums, a bucket travelling on said boom, a hollow chamber directly above said sheaves and said cable passing over said inner sheaves through said chamber and directly over the face of the drums, said drums adapted to selectively drive the bucket in the opposite directions, means for selectively operating either of said drums and means for causing the idle drum to travel in the same direction as the driven drum.

60 In testimony whereof I affix my signature.
CHARLES E. FOOTE.
